[57] CLAIM

The ornamental design for a lever actuator, substantially as shown.

DESCRIPTION

FIG. 1 is a front elevational view of a lever actuator showing my new design;

FIG. 2 is a side elevational view taken from the right of FIG. 1;

FIG. 3 is a rear elevational view thereof;

FIG. 4 is a side elevational view taken from the left of FIG. 1;

FIG. 5 is a top plan view thereof;

FIG. 6 is a bottom plan view thereof;

FIG. 7 is a sectional view taken along line 7—7 of FIG. 2.

FIG. 1

FIG. 2

FIG. 3

FIG. 4

FIG. 5

FIG. 6

FIG. 7
